UNITED STATES PATENT OFFICE.

JOSEPH P. WOLFE, OF DETROIT, MICHIGAN.

SHINGLE.

Application filed February 7, 1927. Serial No. 166,505.

This invention relates to shingles and more particularly to improvements therein tending to simplify, render more efficient and improve generally articles of this character.

5 One of the objects of this invention is to provide a shingle construction formed with a tongue cut from the material of the shingle adjacent one edge thereof and adapted for engagement with notches or recesses formed 10 in the edge of the next adjacent underlying shingle. As a consequence of such a construction it is possible to form the shingles of lighter weight material because the exposed edge of each shingle is hooked under and 15 held down by the edge of an underlying shingle. Shingles constructed in accordance with ordinary practice must be made of a material sufficiently heavy and rigid as to resist the action of wind upon the exposed edge 20 which tends to force or raise the same upwardly.

Another object of my invention and an advantage obtained by reason of the aforementioned construction is that of preventing relative lateral displacement of the shingles. 25 This advantage is obtained by having the longitudinal dimension of the notch or recess substantially the same as the longitudinal dimension of the tongue so that upon engagement of the tongue of one shingle with the recess of another relative lateral displacement between the shingles is prevented. The inter-engaging tongues and recesses of the shingles also provide for automatically spacing 30 the shingles both laterally and vertically.

Another object of this invention is to provide a shingle having means to facilitate the starting of the shingling adjacent, for instance, the edge of the roof and to this end 40 my invention contemplates the provision of notches or recesses along both longitudinal edges of the shingle whereupon a series of shingles may be secured in reversed position upon the roof with the notched straight edges 45 thereof parallel with the edge of the roof to thus provide means whereby the shingling operation can be started with ease and facility. This eliminates the necessity of an objectionable practice now quite universally 50 followed of having on hand a supply of special shingles adapted for starting the shingling operation at the edge of the roof.

The various objects, advantages and novel 55 details of construction of this invention will be made more apparent as this description proceeds, especially when considered in con-

nexion with the accompanying drawings wherein:

Figure 1 is a plan view of a plurality of shingles, constructed in accordance with my invention and illustrating the manner in which they are applied to a roof or the like.

Figure 2 is a plan view of one of the shingles.

Figure 3 is an enlarged detail sectional view taken substantially on the plane indicated by line 3—3 in Figure 1, and

Figure 4 is a perspective view illustrating more in detail the interlocking connection between adjacent shingles.

Referring now more particularly to the drawings wherein like reference characters indicate like parts, it will be noted that I may form my shingle in units or strips 10 each of which comprises a pair of point-down shingle ends 11 thus producing a double or twin shingle unit. However, as will be obvious as this description proceeds, the same advantageous results may be obtained if single shingle units are produced such as indicated by dotted line 12 or if desired units of greater length comprising three or more shingle ends may be produced.

Each unit, and preferably each shingle end 11, is formed with a tongue 13 cut from the material of the shingle and normally lying in the same plane as the body of the shingle until the same is deflected out of this plane for engagement with notches or recesses of adjacent shingles, yet to be referred to. In this connection each shingle unit is provided with one or more recesses 14 in the longitudinal edge adjacent to which the tongues 13 are formed and one or more recesses 15 in the opposite longitudinal edge. 90 These recesses 14 and 15 are formed either by cutting away the longitudinal edge intermediate the ends or by notching the edges at the ends thereof as indicated at 16. Thus the notches 16 of abutting ends of adjacently arranged shingles together form recesses 14 or 15 as suggested by full and dotted lines in Figure 2.

In applying the shingles to a roof or wall, or the like the tongue 13 of one shingle is caused to engage the recess 14 in the edge of the underlying shingle as most clearly illustrated in Figure 3. This not only provides means for holding down the exposed edge of the last applied shingle but also prevents relative lateral displacement between the inter-engaging shingles and provides means

for automatically spacing and aligning successively applied shingles with those previously placed.

The recess 15 arranged in the straight longitudinal edge of the shingle may, by reversing the shingle so that the shingle ends 11 point upwardly instead of downwardly, be brought parallel with, for instance, the edge of a roof and when the shingle is secured in this position to the roof the recess 15 may be engaged by the tongues 13 of the first row of shingles so that the shingling operation may be started with facility and the successively applied shingles properly aligned and spaced. 15 As mentioned hereinbefore this eliminates the necessity of providing special shingles for starting at the edge as is now quite universally the practice.

As was also previously mentioned the tongues 13, which are cut from the material of the shingle, normally lie in the plane of the body of the shingle but when the shingles are applied to a roof or the like the tongue 13 may be conveniently caused to engage the recess 14 by means of a tool inserted through the opening formed by the tongue which tool extends into the recess 14 to guide the tongue into the recess and under the edge of the shingle. After the tool has been removed the shingles are secured to the roof or other surface by nailing the same in the customary manner. When thus secured the tongue or tongues of one shingle are engaged in the recess or recesses 14 of an underlying shingle 30 and extend under the edge of this underlying shingle. 35

While several possible modifications of the herein described and illustrated structure

have been suggested, it will be obvious that various other changes may be made in any 40 of the essential and all of the non-essential details without departing from the spirit and scope of this invention and to this end reservation is made to make such changes as may come within the purview of the accompanying claims. 45

What I claim as my invention is:—

1. A shingle unit formed with a tongue adjacent one longitudinal edge thereof and recesses in the longitudinal edges, said tongue 50 constituting a locking tab adapted to engage the recess in either of said longitudinal edges of an underlying shingle.

2. A shingle unit formed with a tongue adjacent one longitudinal edge thereof and recesses in the longitudinal edges, the recess in one edge being in alignment with the recess in the other edge whereby said tongue may engage one recess of an underlying shingle 55 when the latter is used as a starting shingle, and the other recess when the said shingle is used as an intermediate shingle.

3. A shingle unit comprising a body portion having spaced wings projecting from one longitudinal edge thereof, and tongues 65 formed on said wings, said shingle having a recess in its edge between said wings and a second recess in its opposite longitudinal edge in alignment with the first mentioned recess whereby a tongue may engage one 70 recess of an underlying shingle when the latter is used as a starting shingle and the other recess when said shingle is used as an intermediate shingle.

In testimony whereof I affix my signature.

JOSEPH P. WOLFF.
